UNITED STATES PATENT OFFICE

GEORGE E. WARREN, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY

ART OF MAKING SHOES

Application filed April 20, 1923, Serial No. 633,475, and in Czechoslovakia April 25, 1922. Renewed January 16, 1929.

This invention relates to the art of making shoes. It is herein exemplified as applied in the manufacture of a sole, and specifically an insole, and in the positioning of the sole upon the bottom of a last during the course of the manufacture of the shoe. To facilitate such positioning, an insole and a last having novel structural features are provided and, therefore, the invention includes an insole and a last as articles of manufacture.

10 In the manufacture of welt shoes, particularly, it is desirable, in order to obtain ultimately shoes having the desired shape and attractive appearance, to position the insole accurately on the bottom face of the last both longitudinally and transversely and to maintain such relation until the upper and insole have been secured together in their final relations.

20 A general object of the present invention is to avoid, for securing a sole to a last, the use of tacks, staples or other metallic fasteners such as are commonly employed for that purpose in the manufacture of welt shoes.

25 Accordingly, the invention, in one aspect, comprises a method of making shoes which consists in providing positioning surfaces at separated points on the bottom of a last and providing corresponding positioning surfaces on a sole, one such surface being formed by offsetting the margin of the sole along a portion of its periphery, and locating the sole on the bottom of the last by engaging with each other corresponding positioning surfaces on the respective parts.

The present invention is particularly intended for use in the manufacture of standardized shoes, one type of which is shown and described in a co-pending application 40 of the present applicant, Serial No. 476,659, filed June 11, 1921, but the invention is not limited to use in connection with shoes of that character.

45 In the illustrated mode of practising the method of the invention, the bottom of a last is provided with a plurality of shoulders facing toward the respective ends of the last, with or without a jig hole in the last, and the 50 insole is provided with complementary shoul-

ders or other positioning surfaces. By engaging or alining the respective surfaces, the insole is jigged or positioned exactly and accurately upon the last bottom in predetermined relation to its marginal contour and such positioning is not left, as at present, to the judgment, skill and care of the individual workman. It is to be understood that the invention embraces, also, a last, as an article of manufacture, the bottom of which is provided with shoulders, and, if desired, a jig hole, as and for purposes herein described.

55 Considered in other aspects, the invention includes an insole, as an article of manufacture, which in the form illustrated, has its margin around one or both of its ends offset so as to provide not only the shoulders above mentioned but also recesses for in-turned flanges of the upper of the shoe. Moreover, as illustrated, the insole comprises 60 a plurality of layers of material between the heel ends of which is inserted a reinforcing plate having substantially the contour of the heel end of the insole. This plate serves as 65 a holding means for the nails by which the heel is attached and such reinforcing is particularly useful in a shoe having a short outsole with an incomplete heel portion. Preferably, also, one or more jig holes, which provide positioning surfaces as already explained, are so located in said plate as to aline with corresponding jig holes in the outer or lower layer of the heel portion of the insole but these jig holes do not extend through the inner or upper layer of the insole 70 which, therefore, is smooth and imperforate 75 and covers the jig holes and the nails so as to protect the foot of the wearer of the shoe and avoid the discomfort to him which would result if his foot were to contact with said 80 holes and nails.

85 The invention, as it will preferably be practised, will now be described in detail with the aid of the accompanying drawings in the course of which description still other features of the invention will be pointed out, after which the various features of the invention will be defined in the appended claims.

90 In the drawings, Figs. 1 and 2 illustrate 100

the invention as applied in the method of making shoes in which the insole is applied to the last before it is connected to the upper while the other figures, and particularly Figs. 3 and 4, illustrate the invention as applied to the manufacture of standardized shoes of the type described in my prior application, above referred to.

Fig. 1 is a perspective view of a last which may be utilized in the practise of the invention and which itself constitutes a feature of the invention;

Fig. 2 is a similar view showing an insole mounted upon such a last;

Fig. 3 shows in side elevation, partly in section, a connected upper and insole with a divided last partially inserted therein;

Fig. 4 is a similar view showing the last fully inserted within the shoe;

Fig. 5 is a longitudinal sectional elevation of the heel portion of the completed shoe;

Fig. 6 is a view in perspective and partly in section of a portion of an insole blank and of molding apparatus which may be employed in manufacturing an insole of the specific type shown in Fig. 8;

Fig. 7 is a similar view illustrating a further molding, and the punching, of the insole blank; and-

Fig. 8 is a similar view, partly in section, of a complete insole with the flap at the heel end slightly separated from the body of the insole.

As illustrated, the shoe includes an insole which, as shown in both Fig. 2 and Fig. 8, is provided with a stitch-receiving rib, or lip, 12 and a feather 14 and which is depressed, or offset, both at the toe, as shown at 16, and also round its rear end, as shown at 18, to form two pairs of shoulders 20, 22. The recessed marginal portions 16, 18 compensate for the corresponding relatively thicker portions of the upper materials at the toe and heel of the shoe due to the presence of a box toe and a counter and also, it may be, a toe cap, as indicated in Figs. 3 and 4. The insole is provided with a pair of jig holes 24 for purposes fully explained in my prior application, above mentioned.

Moreover the rear end of the insole, or at least the upper layer thereof, may be split to form a flap 26 and turned back from the body portion, or outer main portion, 28 of the insole on to its shank portion as shown in Figs. 3 and 4, so as to uncover the jig holes 24 and permit their use in jiggling, or accurately positioning, other shoe parts upon the insole in the course of the manufacture of the shoe. One such part, shown in Fig. 5, is a reinforce in the form of a plate 30 which has substantially the contour of the heel end of the insole and which is provided with similar jig holes to aline with the jig holes 24 and which may be placed between the body of the insole 28 and the last, as shown in Figs. 3 and 4 and

which is ultimately covered by the flap 26, as shown in Fig. 5.

According to the broader aspects of the invention, the last 36 may be constructed like ordinary commercial lasts, except as will now be pointed out. The margin of the last bottom at the heel and at the toe is provided with recesses, or rabbets 38, 40, corresponding approximately in shape and location to the offset portions 16, 18 of the insole. The adjacent ends of these recesses terminate in shoulders 42, 44 facing the respective ends of the last and corresponding approximately to the shoulders 20, 22 of the insole. As shown particularly in Figs. 3 and 4, the last comprises separable heel and foreparts which may be inserted successively within the connected upper and insole of a shoe, as more fully explained in my said application. The heel part of the last is provided with a jig hole 46 into which may be inserted a jig pin 48 (Fig. 4). Such a jig hole and jig pin may be utilized in positioning the insole on the last and they may also be utilized in the assembling of the insole with other parts of the shoe.

When practising the invention in the manner illustrated in Figs. 3 and 4, it has been found unnecessary to make the recesses in the last correspond in shape exactly to the recesses in the insole and, therefore, the marginal portions of the last at the heel and toe ends, instead of having distinct shoulders, or rabbets, as shown in Figs. 1 and 2, may be simply beveled, as shown at 50, 52 in Figs. 3 and 4, terminating, however, in shoulders 42, 44 such as are shown in Figs. 1 and 2.

As shown in Fig. 2, the insole is laid directly upon the bottom of the last and is jiggled or accurately positioned thereon in predetermined relation to the contour of the last by direct engagement of the positioning surfaces of the last—namely, rabbets 38, 40 and shoulders 42, 44—with the corresponding positioning surfaces 16, 18, 20 and 22 of the insole. If desired, also, the jig pin 48 may aid in this operation by alining the front jig hole 24 in the insole with the jig hole 46 in the last. These complementary positioning surfaces upon the insole and upon the last respectively may be relied upon to hold these parts in their jigged relation without the aid of any tacks, staples, or the like, such as are employed in ordinary shoemaking, but any suitable holding means may be employed if desired. As fully explained in my prior application, above mentioned, and as illustrated in Figs. 3, 4 and 5 of the present application, the upper, indicated generally by the numeral 54 and usually including a box toe 56, a toe cap 58 and a counter 60, is preferably molded at its ends with inturned flanges 62 and 64 to fit the offset portions 16 and 18, respectively, of the insole and the heel end of the upper is permanently connected to the insole, as

5 by tacks 66, before these parts are applied to the last. However, even in such case the complementary formation on the insole and last, above referred to, aids in accurately locating the insole upon the bottom of the last after it has been inserted, as shown in Fig. 4.

10 As above stated, the present invention also relates to the preparation of an insole of the general type shown in Fig. 8. This insole 10 is made up of two or more layers 15 of suitable material which may include a layer 74 of canvas in which the stitch-receiving rib 12 is molded and to which the other layer or layers 76 are adhesively secured. If desired, the upper or foot-engaging layer may be of leather or imitation leather, or of other coated fabric material presenting a relatively smooth surface along which 20 the foot of the wearer will slide easily as it is being inserted into the shoe.

25 In manufacturing such an insole commercially, it is contemplated that the several layers will be died out more or less closely to, but preferably larger than, their final contour and that then, through the operation of a substantially automatic machine (such, for example as one of the general type fully disclosed in Letters Patent No. 1,667,948, 30 dated May 1, 1928, and issued to the assignee of the present application on a co-pending application filed in the name of Frederick H. Perry), the rib 12 will be molded in the layer 74 of the insole. The other layer or 35 layers 76 will be located accurately and in predetermined relation to the layer 74 and secured permanently thereto by adhesive and under pressure. However, so far as the present invention is concerned, the insole 40 may be built up in a variety of ways and with the aid of simple molding apparatus such as is illustrated diagrammatically in Figs. 6 and 7, wherein a mold 80 is provided with a groove 82 corresponding in outline 45 and depth to the rib 12 to be formed in the layer of canvas 74. In order to produce in the margin of the insole the offset or depressed portions 16, 18, above described, the upper surface of the end, marginal portions 50 of the mold 80 are made somewhat higher than the surface of the adjacent intermediate portion, being joined thereto by short, inclined surfaces or shoulders 84, 86 corresponding to the shoulders 20, 22 on the insole. A co-operating mold 88, Fig. 6, is 55 provided with molding surfaces generally complementary to those of mold 80 just described including a rib 90 shaped to press a portion of the layer 74 of the insole firmly 60 into the groove 82, thus forming the rib 12. After the ribbed layer 74 has been molded, as shown in Fig. 6, the other layer or layers 76 are deposited upon and in predetermined 65 relation to the ribbed layer, adhesive having been previously applied to at least one

of the two layers in any suitable manner, and then all of the layers, while supported by mold 80, are subjected to pressure by a mold 92, similar to the mold 88 but without a rib such as rib 90, until the adhesive has 70 dried sufficiently to insure a secure connection between the layers. Under certain circumstances, it may be preferable first to secure two unribbed layers together permanently and then to apply them as a unit to the 75 ribbed layer 74.

80 As illustrated in Fig. 7, the lower mold 80 has fixed therein two hollow punches 94, corresponding in position and shape to the jig holes 24 to be formed in the insole and these 85 punches project far enough from the upper face of the mold 80 so that when the layer 76 is pressed down upon them by the mold 92, the punches will pass through the body portion 28 of the insole but will not pass through the flap 26 which, therefore, remains imperforate. Thus, as pointed out above and also in my application above referred to, the jig holes 24 are located accurately in predetermined relation to the rib 12 of the insole. 90 Moreover, as illustrated in Fig. 7, each punch includes an internal spring-pressed ejector 95 95 for the punchings, or "pills", and corresponding anvils 98 are mounted in the upper mold 92.

100 Therefore, in the preparation of the insole as above set forth, the blank is subjected to pressure between the molds so as not only to form the upper attaching rib 12 and to secure the layers 74, 76 firmly together but also to offset the margin of the blank 16, 18 at its toe and heel ends into a different plane from the intermediate portions of the blank, thus compensating for the thickness of the box toe, toe cap and counter of the shoe and, at 105 the same operation, the jig holes 24 are punched in the body 28 of the insole but not through the inner flap 26. The slightly raised surfaces produced upon the upper face of the insole by the offset portions 16, 18 not only cause no discomfort to the wearer of the shoe but may even be a distinct advantage in that they tend to cause the insole to fit more closely to the rounded bottom of the foot. 110 The surplus material at the margin of the insole, as shown in Fig. 7, may be trimmed off to locate the edge of the finished insole accurately in predetermined relation to the rib 12 and to the jig holes 24, as shown in 115 Fig. 8 and as set forth in my said prior application. 120

125 Throughout most of the operations performed upon the shoe while it is upon the last, including the attaching of the short outsole 100 and the heel 102, the jig holes 24 in the insole are uncovered because the flap 26 is turned back from the body 28 of the insole, as shown in Figs. 3 and 4 and, as more fully explained in my said application, the heel 130 is jigged with respect to the shoe and in pre-

determined relation to the insole before it is permanently secured thereto by alining jig holes 104 in the heel with the jig holes 24 in the insole after which it is secured by attaching nails 106, the heads of which seat themselves upon the reinforcing plate 30 which serves as a holding means for all of these nails 106. Thereafter, the last is removed from the shoe and the flap 26 is turned back over the reinforce 30 and secured thereto so that, in the finished shoe, the jig holes and nails are concealed by the flap and the foot of the wearer is also protected against irritation therefrom because the insole presents a smooth, imperforate upper surface.

What is claimed is:

1. In the manufacture of shoes, the method which comprises providing positioning surfaces at separated points on the bottom of a last and providing corresponding positioning surfaces on a sole, one such surface being formed by offsetting the margin of the sole along a portion of its periphery, and locating the sole on the bottom of the last by engaging with each other corresponding positioning surfaces on the respective parts.

2. In the manufacture of shoes the method which comprises providing marginal recesses to form positioning surfaces on the bottom of a last and providing corresponding positioning surfaces on a sole by bodily offsetting the margin of the sole at its ends relatively to its central portion, and locating the sole both longitudinally and transversely on the bottom of the last by engaging with each other corresponding positioning surfaces on the respective parts.

3. In the manufacture of shoes, the method which comprises providing shoulders on the bottom of a last at points separated longitudinally and providing complementary shoulders on a sole, and locating the sole in predetermined position longitudinally on the bottom of the last by engaging corresponding shoulders with each other.

4. In the manufacture of shoes, the method which comprises providing in the marginal heel and toe portions of the bottom of a last a plurality of shoulders facing toward the respective ends of the last and providing an insole with complementary shoulders, and then locating the insole in predetermined position longitudinally on the bottom of the last by engaging the respective shoulders with each other.

5. In the manufacture of shoes, the method which comprises providing the bottom of a last with a positioning surface in its toe portion and with a jig pin in its heel portion, also providing an insole with an offset margin at its toe and with a jig hole in its heel portion respectively corresponding in location to said surface and pin in the last, and locating the insole on the bottom of the last with

said offset and hole respectively engaging said surface and pin.

6. In the manufacture of shoes the method which comprises providing corresponding ends of a sole and of a last bottom respectively with an offset margin and a recess extending to their respective peripheries and thereafter applying the sole to the last bottom and locating it thereon by engaging the offset margin and the recess.

7. In the manufacture of shoes, the method which comprises providing the bottom of a last with marginal recesses at its toe and heel ends, also bodily offsetting the margin of an insole at its toe and heel ends into a plane or planes substantially parallel to the faces of the insole and thereafter applying the insole to the last.

8. In the manufacture of shoes, the method which comprises providing the bottom of a last with a recess in its toe portion and with a jig hole in its heel portion, also providing an insole with an offset margin at the toe and with a jig hole in its heel portion respectively corresponding in location to the recess and the hole in the last, securing an upper to the insole and inserting the last within the upper and insole and alining corresponding surfaces on the respective parts to aid in locating the insole on the last bottom.

9. A method of preparing insoles which comprises subjecting an insole blank to pressure between molds so as to offset its margin adjacent to the heel end of the blank into a different plane from the adjacent portions of the blank so as to compensate for an extra thickness of upper material at the corresponding portion of the shoe in which the insole is to be incorporated.

10. A method of preparing insoles which comprises subjecting an insole blank to pressure between molds so as to form in one layer at least thereof an upper attaching rib and so as to offset the margin of the blank bodily at its toe and heel ends into a different plane from the intermediate portions of the blank to compensate for the thickness of the box toe and counter of the shoe in which the insole is to be incorporated.

11. An insole having its margin around its heel end offset with relation to the adjacent portions of the insole to receive an inturned flange of the heel portion of an upper, including a counter, when incorporated therewith in the manufacture of a shoe.

12. An insole having its margin around both its toe and heel ends bodily offset into a different plane from the adjacent portions of the insole so as to compensate for an extra thickness of upper materials at the corresponding portions of the shoe in which the insole is to be incorporated.

13. As an article of manufacture, an insole having a jig hole extending into but only partly through it.

14. An insole comprising a plurality of layers of material and having at its heel end a plurality of jig holes extending through the outer layer but not through the layer which provides the upper face of the insole. 70
- 5 15. An insole comprising a plurality of layers of material and a reinforcing plate having substantially the contour of the heel end of the insole, the outer layer of the insole and the said plate being provided with aligned jig holes but the foot engaging layer of the insole being smooth and imperforate. 75
- 10 16. An insole having at its heel end a plurality of jig holes extending perpendicularly from its outer face but not completely through the insole. 80
- 15 17. A method of preparing insoles which comprises securing together a plurality of layers of material with adhesive between them by exerting pressure thereon and at the same 85 operation punching one or more holes in at least one layer. 90
- 20 18. A method of preparing insoles which comprises pressing together a plurality of layers of material and simultaneously punching one or more holes extending only part way through the combined layers. 95
- 25 19. A method of preparing insoles which comprises subjecting to pressure between 100 molds an insole blank comprising a ribbed layer and a layer having a split end with an adhesive between the layers and simultaneously punching a plurality of jig holes through the ribbed layer and through a part 105 only of the split end of the other layer. 110
- 30 20. A method of making shoes which comprises providing a last having positioning means, forming an insole in such manner that the heel end includes an inner flap and an outer body portion provided with positioning means, locating said insole on said last, with the flap uncovering said positioning means on the insole, by bringing said positioning means on the last into engagement 115 with said positioning means on the insole, attaching other parts including a heel and subsequently laying down the flap over said body portion. 120
- 35 21. A method of making shoes which comprises providing one end of an insole with a flap and the corresponding portion of the body of the insole with one or more jig holes, turning the flap back from said body portion, locating another shoe part in predetermined 125 relation to the insole by utilizing said jig hole or jig holes and securing said part to the insole by fastenings extending into said body portion and thereafter turning back and securing the flap. 130
- 40 22. In a shoe, an insole comprising a plurality of layers, including a reinforcing plate, the inner layer being separate from the next layer at the heel portion thereof, a short outsole, a heel, and fastenings for attaching the heel to the insole and reinforcing plate, the
